UNITED STATES PATENT OFFICE.

WILLIAM THOMAS BUCKINGHAM ROBERTS, OF LEICESTER, ENGLAND, ASSIGNOR TO
UNITED SHOE MACHINERY CORPORATION, OF PATERSON, NEW JERSEY, A COR-
PORATION OF NEW JERSEY.

GRADING MACHINE.

Application filed August 26, 1925, Serial No. 52,591, and in Great Britain September 19, 1924.

This invention relates to grading machines and is herein illustrated as embodied in a machine for stamping and evening shoe soles in accordance with the thickness of the thinnest 5 spot in a selected locality in each sole.

Machines for grading soles and similar blanks commonly comprise measuring mechanism, grading mechanism and mechanism for adjusting the grading mechanism in accordance with the determinations of the measuring mechanism. In the operation of such a 10 machine a blank is presented to the measuring mechanism which is responsive to variations in the thickness of the blank, said measuring mechanism commonly comprising a 15 pair of rolls which advance the blank and one of which rises and falls as thicker or thinner localities in the blank are encountered; and a feed mechanism, commonly an endless chain, 20 feeds the blank from the measuring mechanism to the grading mechanism which has previously been adjusted, during the travel of the blank, into and locked in a position to grade the blank in accordance with the thickness of the thinnest spot in a selected locality 25 of the blank as determined by the measuring mechanism. For many years machines of this type were so constructed that a succeeding blank could not be presented to the measuring mechanism until the preceding blank had 30 been completely graded—for example, split or evened; but recently machines have been designed in which a succeeding blank may be presented to the measuring mechanism while 35 the preceding blank is being graded, with the result that the output of the machine is considerably increased. Such a machine is disclosed in Letters Patent No. 1,640,372, granted Aug. 30, 1927, upon an application 40 filed in my name.

The general object of the present invention is to improve machines of this general type and more particularly to facilitate the operation of machines in which two blanks may be going through the machine at the same time.

Grading machines, whether adapted to permit the passage through them of one blank at a time or of two, have commonly been provided with a member located in the path of travel of the blank and adapted to be displaced by the blank to effect a locking of part of the adjusting mechanism against movement in response to thicker spots in the blank

encountered by the measuring mechanism, this member being held displaced by the blank 55 during the effective measuring operation and returning to its normal position—and thereby releasing the locking means—only after the trailing end of the blank has moved past it. In machines in which two blanks at a time 60 are passing through the machine, a difficulty sometimes arises, when the blanks are of considerable length, by reason of the fact that the trailing end of the preceding blank is holding the locking member referred to above displaced—and the locking means effective—when the succeeding blank has reached a position in which the measuring mechanism 65 should be effective. Owing, however, to the fact that part of the adjusting mechanism is 70 still locked, the measuring mechanism is not effective to adjust the grading mechanism.

According to one feature of the present invention there is provided, in connection with locking means for blank treating mechanism 75 and a locking member adapted when displaced by a blank to render the locking improved means effective, means for releasing the locking means irrespective of whether the blank is still holding the locking member displaced. In the illustrative machine, this 80 means takes the form of a trip adapted to be engaged by the leading end of a blank, said trip, when moved, acting to throw into operation power-operated means for releasing the 85 locking means.

In evening machines in which two blanks at a time may be passing through the machine, it is desirable that the trailing end of the preceding blank be released by the rolls of the 90 evening mechanism at the end of the evening operation so that, should the trailing end of the blank have become stuck between these rolls, it is released then and an opportunity 95 given for it to fall away from the rolls just before the leading end of the succeeding blank enters between the rolls. Otherwise, the succeeding blank is liable to be evened, not to its thickness as determined by the measuring mechanism, but to the determined thickness 100 of the preceding blank provided the preceding blank is thinner than the succeeding blank, or in an indeterminate manner if the preceding blank is thicker.

According to another feature of the invention, means are provided for so releasing the 105

trailing end of each blank after it has been evened. In the illustrative machine, the upper roll of the evening mechanism is urged at all times by resilient means to move away 5 from the lower roll, and is moved down to the proper position for each blank by rotary spiral-faced inclines. Just at the end of the evening operation, these inclines are raised to permit the resilient means to open the gap between the rolls so that the evened blank may 10 fall away. Downward movement of the spiral-faced inclines, which immediately follows them, adjusts the gap suitably for the succeeding blank.

15 In grading machines having evening mechanism, it has been customary to provide two inclined stops upon the bearings of the upper roll of the evening mechanism and, located above them, an adjustable bar carrying 20 two complementary inclined stops, the construction being such that the roll is normally in its lowermost position wherein the two sets of stops are out of contact. In the operation of the machine the bar is adjusted by 25 the measuring mechanism to cause the desired space between the two sets of stops; and then the blank, as it enters between the rolls, raises the upper roll until said stops are in contact, the extent to which the upper roll 30 may be so raised by the blank depending upon the position into which the bar has been adjusted and consequently upon the thickness of the thinnest spot in the blank encountered by the measuring mechanism.

35 According to another feature of the invention, the rolls of the evening mechanism are normally held apart by resilient means, and rotary members are provided for producing relative movement of approach between the 40 rolls to the desired extent in accordance with the determinations of the measuring mechanism. In the illustrative machine, the adjustable bar is adjusted as usual into a position corresponding to the thickness of the 45 thinnest spot in a blank; but it does not carry the usual inclined stops. Instead, its end serves as a gage to limit the movement of a power-actuated member movement of which rotates the rotary members, which have been 50 referred to above, to depress the upper roll of the evening mechanism. With this construction the blank does not have to spread the rolls of the evening mechanism apart, the rolls being adjusted into exactly the desired 55 spaced relation before the blank enters between them.

These and other features of the invention, including certain details of construction and combinations of parts, will be described as 60 embodied in an illustrative machine and pointed out in the appended claims.

Referring now to the accompanying drawings,

Figure 1 is a side elevation of the machine 65 partly in section;

Figure 2 is a plan, partly in section, of some of the parts of the machine;

Figure 3 is a sectional elevation to a reduced scale, showing work feeding and splitting roll separating mechanism of the machine;

Figure 4 is a side elevation, partly in section, showing splitting roll setting mechanism of the machine;

Figure 5 is an end elevation, partly in section, showing splitting roll setting mechanism of the machine;

Figure 6 is a section on the line 6—6 of Figure 4;

Figure 7 is a detail view showing feed chains, presser devices and a clutch tripping member of the machine; and

Figure 8 is a part sectional elevation showing work guiding mechanism of the machine.

In this construction the machine is of the same general nature as that described in British Patent No. 17,808 of 1909 in that it includes a pair of measuring rolls 1 and 2 and a pair of feeding rolls 3 and 4 (hereinafter referred to as splitting rolls) which latter feed the work piece against a splitting knife 5 (Fig. 4), the work pieces being fed under a gate 6 (Fig. 1) to the measuring rolls from a table 7 at the front of the machine by the operator and being conveyed on leaving the measuring rolls by a chain conveyor 8 (Fig. 3) to the splitting rolls. Stamping mechanism is provided at a location slightly in advance of the splitting rolls in order to mark the work, this stamping mechanism (not shown) being like that of the machine of the patent. The means for energizing the stamping mechanism includes, as in the patented machine, a rotary stamp shaft 9 100 clutched intermittently to the main driving shaft 10 of the machine which rotates continuously and causes continuous rotation through gearing of both pairs of rolls 1, 2 and 3, 4 and the conveying chain 8. The tripping into action of the clutch, which connects the rotary stamp shaft 9 to the constantly driven parts, has in constructions heretofore used generally been done by the lifting of the upper splitting roll caused by 105 engagement of the leading end of the work piece therewith. In the illustrative construction, a clutch tripping member 11 is provided which the work engages immediately before entering the bite of the splitting rolls. 110

The clutch tripping member 11 (Figs. 3 and 7) has projecting downwardly from it into the path of the work piece three fingers 12, 13 and 14 one at each side of and one between the conveyor chains 8, two chains being provided in the present machine, so that if the leading point of the work piece is offset from a medial line extending between the conveyor chains one or the other of the side fingers 12 or 14 will be engaged by the 115 120 125 130

leading point of the work piece, and the member 11 will thereby be raised.

The member 11 is fixed to a block 15 by a screw and slot connection so as to be vertically adjustable thereon, and the block 15 has extending from it a stem 16 slidably mounted in the end of an arm 17 and fixed therein by a screw 18. The arm 17 is mounted on a shaft 19, rotatably mounted in the frame of the machine and is rigidly connected to an arm 20 (Fig. 1) also mounted on the shaft 19. The arm 20 has pivotally connected to it at 21 the lower end of a clutch trip rod 22 which at its upper end engages a block 23 fixed on a clutch lever 24. When the member 11 is raised by the leading end of the work piece, the rod 22 is raised to swing the lever 24 in an anti-clockwise direction to close the clutch. The clutch members 20 may be the same as the corresponding members in British Patent No. 17,803 of 1909, that is two pinions one of which is shown at 201, said pinions having clutch teeth on their end faces and being adapted to be moved into clutching relation by a spring when the lever 24 is swung in an anti-clockwise direction. As the rod 22 is raised, a cam face 25 on the rod engages a roll 26 and the rod is swung about its pivot 21 and its upper end removed from the block 23, so as eventually to permit the lever 24 to swing back to the position shown so as to open the clutch again. The gearing between the driving shaft 10 and stamp shaft 9 is such that the driving shaft 35 makes three revolutions to one of the stamp shaft 9; and, to prevent the clutch lever 24 from swinging in a clockwise direction and opening the clutch before the shaft 9 has completed a revolution, a cam lever 27 is pivoted on the machine frame and is actuated by a cam on the shaft 9 so that through a pin 28 on the lever 24 the lever is held away from clutch-opening position until the shaft 9 has nearly completed a revolution when the lever is allowed to swing in a clockwise direction to open the clutch. The roll 26 is carried on an arm 29 of a cam lever 30 pivoted at 31 to the machine frame, this cam having two other arms 30' and 65 for purposes presently to be described.

The stamping mechanism (not shown) may be like that of the British patent referred to above and comprises a stamping member which, by the rotation of the shaft 9, is first lifted against the tension of a heavy spring and is then released. As will presently appear, the upper roll 3 of the splitting mechanism is not lifted by the pieces of stock as they pass beneath it. In the patented machines, as has been mentioned, this lifting of the upper roll of the splitting mechanism is utilized to trip the clutch which causes operation of the stamping mechanism. In the present machine the clutch which causes operation of the stamping mechanism is

tripped by the passage of the leading end of the pieces of stock beneath the fingers 12, 13, 14 at the end of the trip member 11.

The gate 6 in front of the measuring rolls 1 and 2 being lifted as will be hereinafter described, a work piece is fed in by the operator, thus depressing the lower measuring roll 2 as is usual in machines of this class. The up and down movements of the roll 2, due to variations in the thickness of the pieces of stock, causes movement of a slide bar 37 or controller (Fig. 2) to and fro above the rolls of the splitting mechanism, such movement being caused, as in the machine of the patent, by a segment lever 32 (Fig. 1), segments 33, 34, rack bar 35 and vertical shaft 36 having at its lower end a pinion meshing with teeth formed on the side of the bar 35 and at its upper end a pinion meshing with teeth formed on the side or edge of the bar 37. This slide bar must finally be set in a position to correspond to the thickness of the thinnest spot in the piece of stock which is passing through the measuring rolls 1 and 2, since its final position, as in the machine of the reference, determines the setting of both the stamping and the splitting mechanisms. To this end the slide 37 has fixed to it two ratchet blocks 38, 39 one above the other and provided with teeth 40, 41 facing in opposite directions. Adapted to engage these sets of teeth are two pivoted pawls 42, 43 pivoted in a forked member 44 slidably mounted in the frame of the machine and adjustable by means of a screw 45. The member 44 may be locked in adjusted position by a screw (not shown). The pawls are provided with spring pressed plungers 46, 47 which cause them to engage the teeth on the ratchet blocks 38, 39. As will presently appear, the pawl 43 engages the teeth 41 so as to permit movement of the slide bar 37 for a time only in a direction corresponding to thinner spots encountered in the piece of stock which is passing between the measuring rolls 1, 2; and then the pawl 42 engages the teeth 40 so that the slide bar 37 can no longer move in either direction. The pawls are normally held out of contact with the teeth, as shown by rods 48, 49, which are actuated at the proper times to release the pawls. The movements of the rod 49 are controlled by the vertical movements of a shoe 50 (Fig. 1) which is raised when the leading end of a piece of work passes beneath it and falls when the trailing end passes from beneath it. The shoe 50 is adjustably mounted on a rod 51 and carries a spring plunger 52 arranged to enter any one of a row of holes 53 in the rod 51. The rod 51 is fixed in the hub of an arm 54, pivoted to the frame of the machine, which has formed on it a face 55 against which the end of a bar 56 bears. The bar 56 is slidably mounted in the frame of the machine and has fixed in it the end of the rod 49, so that when the leading end of the work

piece enters beneath the shoe 50 and lifts it about the pivot 203, the slide 37 is locked in one direction by pawl 43; and, when the shoe 50 drops off the trailing end of the work piece, 5 the pawl 43 is withdrawn from the teeth 41. The other pawl 42 is tripped to lock the slide 37 in the other direction by a connection between its rod 48 and the gate 6 which gate drops when the trailing end of the work piece 10 has passed from under it. This connection comprises an arm 57 fixed to the shaft 19 and having at its upper end a pin 58 through which the rod 48 is threaded. The gate 6 is slidingly mounted on rods 59, 59 one of which 15 is fixed in the hub of the arm 57 and the other in a block 60 fixed on the same shaft 19 to which the arm 57 is fixed. By adjusting the gate 6 along the rods 59, the length of that portion of the work piece which is between 20 the gate and the bite of the feed rolls when the gate drops off the work piece and which is not measured may be varied.

The machine is designed to come to rest with the gate 6 raised and the shoe 50 lowered 25 as shown in the figures, both locking pawls 43, 42 being held in inoperative position (Fig. 2). As soon as a piece of stock is pushed beneath the gate and engaged by the measuring rolls 1 and 2, the gate falls upon the piece 30 of stock. The gate does not at this time fall far enough to allow the pawl 42 to become operative. As soon as the piece of stock lifts the shoe 50, the pawl 43 becomes operative to prevent the slide 37 from moving to 35 the right (Fig. 2) in response to thicker spots in the stock which is passing between the feeling rolls 1, 2. The slide 37 is, however, free to move to the left in response to thinner spots encountered in the stock by the measuring 40 rolls. The slide 37 thus continues to be moved to the left, as thinner spots are encountered in the stock, until the gate 6 rides off from the trailing end of the stock, whereupon the pawl 42 becomes operative, and the slide 37 45 is locked from movement in either direction, said slide at that time occupying a position dependent upon the thickness of the thinnest spot in the piece of stock to which the measuring mechanism was responsive.

50 In the machine of the patent referred to above, the member corresponding to the slide bar 37 carries two wedge-shaped stops which cooperate with two complementary wedge-shaped stops on the bearings of the upper roll 53 of the splitting mechanism so that, when the slide bar has been set in accordance with the thinnest spot in the stock and locked from movement, it is so held while the stock is passing through the splitting mechanism and 55 is not released until the stock passes from between the rolls 3 and 4 after having been completely split. In the present machine the slide bar 37 carries no such stops and is released while one piece of stock is being split 60 so that it may be responsive to the measure-

ments of a succeeding piece of stock. It is not released, however, until it has served as a gage to set certain stops presently to be described, which serve to determine the position of the upper roll 3 and hence the thickness to which the stock is split. To this end, the setting slide 37 has a beveled surface 61 (Fig. 2) at its right-hand end into contact with which a complementary beveled surface on a slide member 62 is adapted to be brought to set the stops referred to above in a manner which will be described below. The mechanism for causing this contact takes the form of a closed cam track 63 (Figure 1) in a gear wheel 64 mounted on the stamp shaft 9 as will be hereinafter described. The cam 64 has in it a second cam track which operates the lever 30 to a second arm 65 to which a bar 66 is pivoted which latter is adapted to move horizontally for lifting the gate 6 as soon as the setting of the splitting rolls allows of the introduction of a fresh work piece. The bar 66 is swung upwardly by a spring (not shown) and has fixed on it a block 67 arranged to engage a plate 68 fixed on an arm 69 which is fixed on the shaft 19. The bar 66 is swung downwardly to allow the gate to fall upon the work piece by an arm 70 which is fixed to the shaft 71 on which the segment arm 32 is fixed and which swings down when the lower measuring roll 2 is depressed by the work piece and engages a pin 72 in the bar.

In this construction the limit to which the upper splitting roll 3 can be lifted, is set by two rotatable stop members 73, 74 (Fig. 5) having spirally inclined faces 75, 75 and adapted to rotate on vertical axes positioned directly above complementary spiralled blocks 76, 77 mounted on the top sides of the bearing blocks 78, 79 of the upper splitting roll.

The two rotary spirally inclined stop members 73, 74 carry pinions 80, 81 which are connected by a rack bar 82 extending across the machine; and the pinion 81 is also connected to rack teeth formed on a bar 83 (Fig. 2) operated by the closed cam track 63 (Fig. 1) in the gear wheel 64, said bar 83 being slidable backward and forward in the machine and being connected at the proper time, as will presently appear, to the wedge member 62 which engages the beveled end of the setting slide 37. The member 74 is provided with a circular ratchet 84 (Fig. 2) which is engaged by a pawl 85 so that the incline members 73, 74 cannot return against the movement given them as described until the pawl is released. The pawl 85 is urged by a spring 86 towards the ratchet wheel and is controlled by a lever comprising arms 87, 88 (Fig. 1) fixed on a shaft 89 rotatably mounted in the frame. The arm 87 carries a cam roll 90 which engages a cam 91 on the gear wheel 64 so that the pawl 85 is with- 130

drawn from the teeth as soon as the shaft 9 begins to rotate.

The cam track 63 in the gear wheel 64 operates a lever 92 pivoted at 93 to the machine frame and connected by a link 94 to one arm 95 of a bell-crank lever pivoted at 96 to the frame. The other arm 97 of the bell-crank lever is forked and has pivotally mounted in it a sleeve 98 through which 10 passes transversely a rod 99 (Fig. 6). Slidingly mounted in the axial bore of the sleeve are plungers 100, 101 urged towards the rod 99 by a spring 102. The plungers 100, 101 have frusto-conical inner ends for engagement 15 with a peripheral groove on the rod 99. The rod 99 is pivotally connected at 103 (Fig. 4) to the bar 83. The bar 83 has pivoted to it at 104 a latch 105 having a hooked end 106 for engagement with a recess 107 in a 20 slide 108 on which the wedge member 62 is formed. The hooked end of the latch is swung upwardly about its pivot 104 by a spring 109 connected to an arm 110 of the latch and to a pin 111 in the rod 99, and its 25 upward movement is limited by the engagement of a tail piece 112 on the latch with the slide 83. The latch is pressed downwardly about its pivot 104 to disengage it from the recess by a cam 113 on the shaft 9. The slide 30 108, when released by the latch 105, is pulled against a stop 114 by a spring 115 connected to the slide and to a pin 116 in the stop. The upper splitting roll 3 is urged upwardly at 35 all times, so that the spirally inclined faces on the blocks 76, 77 are always in contact with the spirally inclined faces on the rotatable members 73, 74; and, as the members 73, 74 are rotated, the upper roll rises or falls. With this construction there is always 40 a substantial gap between the upper roll 3 and lower roll 4 to receive the leading end of a work piece as it comes to the rolls to be split and, as will hereinafter appear, the rolls 45 part to release the trailing end of the split work piece should it have caught between the upper smooth-faced roll and the knife.

The upper splitting roll 3 is raised by a spring 116* (Figure 3) connected at one end to the machine frame and at the other end 50 to a collar 117 loosely mounted on a rod 118 and confined lengthwise of the rod by flanges on the rod. The rod is screwed through a pin 119 rotatably mounted in an arm 120 of a lever 121. The lever 121 is pivoted on a 55 shaft 122 carried in a bracket 123 fixed to the frame of the machine and has two horizontal arms, one of which is shown at 124. The arms 124 have pivotally connected to them two curved rods, one of which is shown 60 at 125, which extend upwardly and engage pins 126 on the bearing blocks 78, 79 of the upper roll and thereby lift it to keep the spiral wedges in contact.

The setting slide 37, having had its measurement transferred by the beveled member

62 to the spiral faced members 73, 74, has to be returned for a fresh measurement. Before it can be returned it is necessary to unlock both the pawls 42, 43 previously mentioned. When short work pieces are being 70 operated upon, the under pawl 43, being the one that was first engaged, becomes released by the passing of the rear end of the work piece from under the trailing shoe 50 referred to. When comparatively long work pieces 75 are being dealt with however, there would be undue time loss if the presentation of the succeeding work piece to the feeling rolls 1 and 2 were held up until the preceding work piece cleared the trailing shoe, and so supplementary mechanism is employed to disengage the pawl 43. This supplementary mechanism comprises an additional slide bar 127 (Fig. 1) moving backwardly and forwardly in the machine and operated by the 80 cam operated lever 30 which effects the lifting of the gate. As the cam operated lever 30 moves to open the gate, the additional slide bar 127 moves towards the rear of the machine and causes an auxiliary pawl 128 carried on a horizontal pivot 129 on the operating bar 56 of the lower pawl 43 of the splitting mechanism to drop into a notch 130 in the additional slide bar 127. The operating rod 49 of the lower pawl 43 is thus carried rearwardly and causes that pawl to be released. The auxiliary pawl 128 is controlled by a rod 131, passing through a stud 132 in the arm 54, and having on it a collar 133 and a spring 134. When the shoe 50 is resting on 90 the work, the pawl 128 will be swung down and will bear on the upper surface of the bar 127. When the shoe 50 finally drops as the rear end of the work passes beneath it the pawl 128 is lifted out of the notch. The pawl 105 42 of the splitting mechanism, being connected to the gate, is released as the gate is lifted.

Assuming that the work piece is long enough so that a portion of it is beneath the shoe 50 when the gate 6 is raised through the swinging of the arm 30, when that arm is swung in a clockwise direction, a second arm 30' which is rigid with the arm 30 is 110 swung in the same direction and, through link 206, pulls the slide bar 127 to the left, as viewed in Figure 1. The pawl 128 is at that time in engagement with the notch 130 in the bar 127; and consequently the rod 49 is pulled to the left and releases the pawl 43 115 (Fig. 2) from engagement with its ratchet 39. The raising of the gate having released the pawl 42, the slide bar 37 is free to move; and a second work piece may be presented to the feeling rolls. If, on the other hand, the work piece is a short one, the shoe 50 will ride off from its trailing end before the gate is raised and will, by its descent, release the pawl 43 and at the same time lift the pawl 128 from the notch 130.

In order that the point on the work piece on which the stamp drops may be varied, the gear wheel 64 is connected to the stamp operating shaft 9 by a spring plunger 134 which 5 can be engaged at a plurality of points 135 upon a hub rigidly fixed to the shaft so that the latter may be rotated to different positions in any of which it may be locked to the cam.

10 It is desirable in machines of this general type to provide means for varying the setting of the upper roll of the splitting mechanism for a given adjusted position of the setting slide 37 so that the pieces of work may be split 15 exactly to the thickness of the thinnest spot as determined by the feeling rolls or to a slightly greater or less thickness as may be desired. Referring more particularly to Figure 5, the inclines 73, 74 are manually adjustable vertically in a head which is rigid with the frame of the machine. These inclines have stems 137, 137 projecting vertically upwards, bearing at their upper ends against the underside of bushings 138 screwed 20 into the head. The stems are held up against the bushings by reduced portions 139 of the stems passing vertically through the bushings and having collars 140 on their upper ends. In order to adjust both inclines simultaneously, the bushings are connected by a manually movable cross bar 141 (Fig. 4) pivotally 25 connected to arms 142 clamped to the bushings which allows of their being moved simultaneously when lock nuts 143 holding 30 them relatively to the frame are freed. The bushings may be adjusted independently if the arms 142 are temporarily unclamped.

In the present construction in order that the upper surface of the conveyor chains 8 40 may be brought at their ends as close as possible to the two pairs of rolls 1, 2 and 3, 4 the chains run at their ends on small supporting rollers 144, 145 and are driven by a sprocket wheel 146 (itself driven in the usual 45 manner from the constantly rotating mechanism) which is positioned between and under the end rollers, the chains passing below it and being held in contact with it by an additional freely rotatable roller 147 carried 50 on a lever 148 pivoted on the sprocket wheel shaft 149 and adjustable about its pivot by a screw 150. In this construction two chains, as shown in Figure 7, are used, the shoe 50 above referred to being positioned between 55 the chains.

Work piece positioning guides 151, 151 are provided in front of the gate 6. The guides are pivoted at 152 to slides 153 mounted on the table 7. The guides may be turned down 60 about their pivots into an inoperative position if desired and are held in operative position by spring plungers 155 which enter recesses formed in blocks 156 fixed in the slides 153. The slides 153 are adjustable towards or from each other by a right and left

threaded screw 157 rotatably and slidably mounted in the table 7 and having fixed on it a hand wheel 158. Fixed on the screw 157 are two collars 159, 160 between which extends a lug 161 slotted to embrace the screw 70 157 and projecting from a sleeve 162 threaded to receive a screw 163 rotatably mounted in the table 7 and prevented from movement endwise by collars 164, 165. The screw 163 has fixed on it a hand wheel 166 by which 75 it may be rotated to adjust the guides 151, 151 together laterally of the machine.

The presser member which holds the work pieces upon the chain may conveniently comprise the two bars 170 (Fig. 3) mounted so as to yield independently at each end and having formed around their peripheries grooves in which are supported balls 171 the balls travelling along and around the bars 80 as the work pieces are fed under them.

In the operation of the machine a work piece is presented beneath the gate 6 to the feeling rolls 1 and 2. As the work piece enters the bite of the rolls the lower roll is moved downward and through the segment arm 32, gear segments 33, 34, rack bar 35 and shaft 36 the slide bar 37 is moved across the machine. Downward movement of the segment arm 32 causes, through the arm 70 and pin 72 the block 67 to be withdrawn from the block 68 90 and thus allows the gate 6 to drop onto the work piece but does not allow the gate to drop far enough to bring the pawl 42 into engagement with the teeth 40 on the block 38. As the work piece travels through the machine 95 its leading edge passes under and raises the shoe 50 and thereby allows the pawl 43 to be moved by its spring plunger into engagement with the teeth 41. The slide 37 is thus prevented from moving further in that direction 100 in which it would move if the work piece increased in thickness; but, owing to the shape of the teeth on the pawl 43 and the block 38, it can move in the opposite direction 105 if the work piece decreases in thickness, and the thinnest measurement of the thickness of the work piece is therefore recorded by the position across the machine of the slide 37.

When the gate 6 drops off the trailing end 110 of the work piece the pawl 42 is moved into engagement with the teeth 40, and the slide 37 is then locked against movement in either direction. When the leading end of the work piece passes under the clutch tripping member 11, the clutch associated with the shaft 10 115 is closed through upward movement of the bar 22, and the shaft 9 commences to rotate. During the first part of the rotation of the shaft 10 the cam 91 acts upon the roll 90 to withdraw the pawl 85 from the teeth 84 to 120 unlock the rotary stop members 73, 74 so that they may be set in accordance with the position of the slide 37. Just after the stop members are unlocked, the cam lever 92 is swung in a clockwise direction to move the 125 130

slide 83 towards the rear of the machine so that the latch 105 may snap under and engage the recess 107 in the slide 108. The cam lever is then swung in the opposite direction and moves the slide 83 and slide 108 which are then connected by the hook 106 forwardly until the block 62 on the slide encounters the wedge face 61 on the wedge slide 37. Movement of the slides 83, 108 is thus arrested, and the stop members 73, 74 are set round about their axes a distance depending upon the setting of the slide 37. During the continued movement of the arm 97 the plungers 100, 101 move out of the groove in the rod 99. The pawl 85 then re-engages the ratchet teeth 84 to lock the wedge members 73, 74 in their set position. As the members 73, 74 are rotated in the manner described, the upper splitting roll 3 is moved down by reason of the engagement of the inclined faces against the action of the spring 116 and is set a distance above the knife edge corresponding to the thickness of the thinnest portion of the work piece measured by the feeling rolls; and the splitting rolls are thus set in separated relation to receive the work piece.

The splitting mechanism now having been set and locked, the slide 37 may be returned and the gate opened and a second work piece presented to the feeling rolls to be measured while the first work piece is being split. To free the slide 37 so that it may return to initial position, the pawls 42, 43 are withdrawn from the teeth 40, 41. The pawl 42 is withdrawn by the lifting of the gate which is effected by the cam lever 30, bar 66 and arm 69 as the bar 66 moves towards the front of the machine. The withdrawal of the pawl 43 is effected either by the dropping of the shoe 50 off the trailing end of the work piece, if this has occurred, or by the bar 127, notch 130 and pawl 128 if the shoe 50 has not dropped. When the slide 37 is unlocked, it is returned to its starting position by the springs 180 (Fig. 1). The latch 106 is released from the slide 108 by the cam piece 113 on the shaft 9, and the slide is returned by the spring 115. As the cam lever 30 swings in an anti-clockwise direction to lift the gate, the roll 26 rides up the cam face 25 and allows the rod 22 to be moved by a suitable spring, not shown, under the block 23; and, as the shaft 9 completes its revolution, the lever 27 is swung about its pivot to allow the clutch arm 24 to swing towards the shaft 10 to open the clutch.

As has been described above the plungers 100, 101 move out of the groove in the rod 99 when the arm 97 continues its movement after the block 62 engages the face 61 on the slide 37. During the movement of the arm 97 in the opposite direction, when the clutch on the shaft 10 is closed and the gear 64 begins to rotate, the plungers again enter the groove, and the rod and slide 83 are moved towards the rear of the machine as has been described

to return the members 73, 74 to zero position and to re-engage the latch 105 with the notch 107. As the members 73, 74 are thus returned, the upper splitting roll 3 is raised by its spring 116* and momentarily opens the gap 70 between the roll and knife so that, should the rear end of a work piece have become stuck between these two and not fed out of the machine, it is released then and an opportunity given for it to fall away just before the leading end of the next work piece reaches the splitting rolls.

Having thus described my invention, what I claim as new and desire to secure by Letters Patent of the United States is:

1. A machine of the class described having, in combination, measuring mechanism, grading mechanism, a controller for the grading mechanism adapted to be adjusted in accordance with the determinations of the measuring mechanism, a member located in the path of travel of the blank from one mechanism to the other and adapted, when displaced by the blank, to effect a locking action upon the controller and to terminate the locking action when the blank has moved past it, and auxiliary means independent of the grading mechanism for automatically terminating said locking action if the blank exceeds a given length irrespective of whether it is still in engagement with the member.

2. A machine of the class described having, in combination, measuring mechanism, grading mechanism, a controller for the grading mechanism adapted to be adjusted in accordance with the determinations of the measuring mechanism, a member located in the path of travel of the blank and adapted, when displaced by the blank, to effect a locking action upon the controller, a second member independent of the grading mechanism and also located in the same path, and means operated by displacement of said second member by the blank for terminating said locking effect.

3. A machine of the class described having, in combination, measuring mechanism, grading mechanism, a controller for the grading mechanism adapted to be adjusted in accordance with the determinations of the measuring mechanism, means for feeding a blank from one mechanism to the other, a member located in the path of feed movement and adapted, when displaced by the blank, to effect a locking action upon the controller and to maintain the locking action while displaced, and means for terminating the locking action when the leading end of the blank reaches a given point beyond the member and spaced from the grading mechanism, whereby the controller may be rendered responsive to the measurements of a succeeding blank presented to the measuring mechanism while said member is still held displaced by the preceding blank.

4. A machine of the class described hav-

ing, in combination, measuring mechanism, grading mechanism including co-operating feed rolls relatively adjustable toward and from each other to provide between them a gap the distance across which is controlled by the determinations of the measuring mechanism, and means for causing widening of the gap at the end of each grading operation.

5. A machine of the class described having, 10 in combination, measuring mechanism, splitting mechanism including co-operating feed rolls relatively adjustable toward and from each other to provide between them a gap the distance across which is controlled by the determinations of the measuring mechanism, and means for causing widening of the gap at the end of each splitting operation.

6. A machine of the class described having, 20 in combination, measuring mechanism, grading mechanism including co-operating feed rolls, means for feeding a blank from one mechanism to the other, the construction and arrangement being such that the measuring mechanism may be operating upon a succeeding blank while a preceding blank is passing through the feed rolls, and means operating before said preceding blank reaches the grading mechanism to adjust one of said feed rolls into a position spaced from the other a distance dependent upon the determinations of the measuring mechanism with respect to said preceding blank.

7. A machine of the class described having, 30 in combination, measuring mechanism, grading mechanism including a pair of co-operating rolls, means for feeding a blank from one mechanism to the other, the construction and arrangement being such that the measuring mechanism may be operating upon a succeeding blank while a preceding blank is passing through the feed rolls, and means for relatively adjusting said rolls in accordance with the determinations of the measuring mechanism in such manner that the distance between the rolls is at no time less than the thickness of the thinnest spot in said preceding blank which was encountered by the measuring mechanism.

8. A machine of the class described having, 40 in combination, measuring mechanism, splitting mechanism, means for feeding a blank from one mechanism to the other, the construction and arrangement being such that the measuring mechanism may be operating upon a succeeding blank while a preceding blank is passing through the feed rolls, and means operating before the blank reaches the splitting mechanism for relatively adjusting the rolls in such manner that the distance between them is substantially equal to the thickness of the thinnest spot in said preceding blank as detected by the measuring mechanism.

9. A machine of the class described having, 50 in combination, measuring mechanism,

grading mechanism including a plurality of rolls, resilient means tending to hold the rolls apart, and means for moving one roll toward the other in accordance with the determinations of the measuring mechanism, 70 said means comprising a plurality of rotary shafts and rotary stops carried thereby.

10. A machine of the class described having, 75 in combination, measuring mechanism, grading mechanism including a plurality of rolls, resilient means tending to hold the rolls apart, and means for moving one roll toward the other in accordance with the determinations of the measuring mechanism, said means comprising a plurality of rotary shafts 80 extending perpendicularly to the axes of the shafts of the rolls.

11. A machine of the class described having, 85 in combination, measuring mechanism, grading mechanism including a plurality of rolls, resilient means tending to hold the rolls apart, and means for moving one roll toward the other in accordance with the determinations of the measuring mechanism, said means comprising rotary stops having spirally inclined faces.

12. A machine of the class described having, 90 in combination, measuring mechanism, evening mechanism including feed rolls, resilient means tending to hold the rolls apart, and means for producing relative movement of approach between the rolls, said means including a controller adjustable into a position determined by the operation of the measuring mechanism, a plurality of rotary shafts, and power-operated means for rotating said shafts to an extent determined by the adjusted position of the controller.

13. A machine of the class described, having, 95 in combination, measuring mechanism, grading mechanism, clutch-controlled power-operated mechanism for setting the grading mechanism in accordance with the determinations of the measuring mechanism, means including a chain and a cooperating presser 100 for feeding a blank from the measuring mechanism to the grading mechanism, and a clutch-tripping member located in the path of travel of the blank and having spaced blank-engaging portions arranged to straddle 110 the chain and the presser.

14. A machine of the class described, having, 115 in combination, measuring mechanism, grading mechanism, power-operated mechanism to set the grading mechanism in accordance with the determinations of the measuring mechanism, a plurality of feed chains for feeding a blank from the measuring mechanism to the grading mechanism, and a member having a plurality of blank-engaging portions arranged to extend between and on both sides of the chains and adapted to be displaced by the blank in its travel to cause the power-operated setting mechanism 125 to be thrown into operation.

15. A machine of the class described having, in combination, measuring mechanism, grading mechanism adapted to be adjusted in accordance with the determinations of the measuring mechanism, means for feeding a blank from one mechanism to the other, and a presser for holding the blank against the feeding means, said presser comprising an endless raceway and a plurality of balls 10 therein.
16. A machine of the class described having, in combination, measuring mechanism, grading mechanism adapted to be adjusted in accordance with the determinations of the measuring mechanism, a plurality of chains 15 for feeding a blank from one mechanism to the other, and a plurality of pressers co-operating one with each chain, each presser
- comprising a bar having extending around it a raceway filled with balls. 20
17. A machine of the class described having, in combination, blank treating mechanism, a controller for the treating mechanism adapted to be adjusted into different positions, a member located in the path of travel 25 of the blank through the machine and adapted, when displaced by the blank, to effect a locking action upon the controller and to terminate the locking action when the blank has moved past it, and auxiliary means for 30 terminating said locking action if the blank exceeds a given dimension.

In testimony whereof I have signed my name to this specification.

WILLIAM THOMAS BUCKINGHAM ROBERTS.
